(57) **CLAIM**

The ornamental design for multi-purpose paper holder and pen, as shown and described.

DESCRIPTION

FIG. 1 is a perspective view of multi-purpose paper holder and pen showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top view thereof;

FIG. 7 is a bottom view thereof;

FIG. 8 is a second perspective view thereof with the sheet of paper depicted by means of broken lines being shown for illustrative purposes only and forming no part of the claimed design; and,

FIG. 9 is a third perspective view in an exploded condition.
